UNITED STATES PATENT OFFICE

PRINCE A. GARDNER, JR., OF ST. LOUIS, MISSOURI

DESIGN FOR A BILL FOLD

Application filed July 13, 1931. Serial No. 40,527. Term of patent 14 years.

To all whom it may concern:

Be it known that I, PRINCE A. GARDNER, Jr., a citizen of the United States, residing at the city of St. Louis, State of Missouri, have invented a new, original, and ornamental Design for Bill Folds, of which the following is a specification, reference being had to the accompanying drawing, forming part thereof.

The drawing is a perspective view of an open bill fold showing my new design.

I claim:

The ornamental design for a bill fold, as shown.

PRINCE A. GARDNER, JR.
